UNITED STATES PATENT OFFICE

ALPHONSIUS LONERGAN, OF NEW YORK, N. Y.

ELECTRIC PROGRAM-INDICATOR.

No. 920,163.

Specification of Letters Patent.

Patented May 4, 1909.

Application filed March 31, 1906. Serial No. 309,205.

To all whom it may concern:

Be it known that I, ALPHONSIUS LONERGAN, a citizen of the United States, residing at New York, in the county of New York and State of New York, have invented certain new and useful Improvements in Electric Program-Indicators, of which the following is a specification.

The invention relates primarily to an electric program indicator designed to present to the view of an audience in illuminated form the successive acts of an entertainment.

The main object of the present invention is the provision of means whereby the acts or specialties in any particular program of entertainment may be presented to the audience in the form of an illuminated sign, so as to advise the audience of the act about to be staged, the construction providing a simple device which is capable of extended use and arranged to instantly illuminate any desired sign of the series.

The invention will first be described in the following specification, reference being had particularly to the accompanying drawings, in which:

Figure 1 is a view in elevation of an indicator constructed in accordance with my invention, Fig. 2 a vertical central section of the same, Fig. 3 a broken edge view of the same, Fig. 4 a diagrammatic view illustrating the lamp connections.

Referring particularly to the drawings my improved indicator comprises a face plate 1 which may be of any size or ornamental outline desired, formed with a series of rectangular openings 2, corresponding in number to the number of acts to be indicated. The upper and lower edges of each opening are provided with flanges 3 and 4 respectively, secured on the inner side of the face plate slightly beyond the adjacent edges bounding the opening. The free or inner edges of the flanges are bent toward each other to provide lips 5 extending parallel with the face plate but spaced a determinate distance therefrom. This construction provides guide ways for the reception of the signs to be later described, it being understood that said guideways extend practically the full width of the face plate.

A casing 6, of box like form is secured to the face plate 1, being of a size to wholly enclose the openings 2 and serving as a support for the illuminating means. The casing is preferably hinged at 7 to the face plate and is

formed in one side wall with openings 8 to register with and include each pair of guideways 3 and 4, whereby to permit introduction and removal of the signs.

The illuminating means comprises preferably incandescent lamps arranged transversely of and secured to the rear wall of the casing. The lamps of each series are arranged about centrally and along the longitudinal line of the immediately adjacent opening 1, each set of lamps being in series arrangement with main conductors 10 and 11, a switch 12 being provided for each set of lamps. By this construction any particular set of lamps, and thereby the corresponding opening 2 may be illuminated as desired.

The sign proper comprises a backing plate 13 of semi-opaque material, as frosted glass, on which the data to indicate the particular act is to be stenciled, preferably by water colors. In front of the backing plate is arranged a strip of fabric 14, preferably a white piece of linen, and in front of the strip 14 is arranged a piece of plain glass 15, the section of plain glass serving primarily to maintain the fabric strip in contact with the backing plate.

In the use of a sign of this nature the letter stenciled on the backing plate will be in effect projected onto the fabric strip, owing to the comparatively opaque nature of the backing plate, thus diffusing the illumination and rendering the letters clearly legible through the plain glass. Furthermore, the use of a backing plate of the character described and the forming thereon of the letters in the manner stated provides for the continuous reuse of said backing plate for other signs, as the letter of any particular signs may be readily effaced therefrom by the use of a dampened cloth or the like.

The sign proper comprising the backing plate, fabric strip, and front plate are to be introduced into the respective guides to arrange the lettering on the back plate in front of the lamp and within the outline of the opening, so that the operator by moving the proper switch can instantly illuminate any particular sign of the series in accordance with the act to be staged.

The indicators are to be arranged at the side of a stage in view of the audience, while the switches controlling the lamp will, of course be arranged upon a stage proper for operation as desired.

The device as a whole provides a simple

form of indicator in the use of which a sign indicating an act to be staged may be quickly presented to the view of an audience, the construction providing for the continual reuse of a sign proper in the manner described.

Having thus described the invention what is claimed as new, is:—

10 A program indicator comprising a face plate with a series of continuous transverse openings therein having the inner faces of their upper and lower edges provided with flanges which are bent in angular form, to provide guideways which extend entirely 15 across the face of the plate, a sign slidably

mounted in said guideways, said sign consisting of a sheet of frosted backing having letters thereon, said backing being provided with a sheet of fabric attached thereto having a sheet of glass therewith, a box casing 20 hinged to said face plate, and illuminating means carried by said casing substantially as specified.

In testimony whereof I affix my signature in presence of two witnesses.

ALPHONSUS LONERGAN.
